(57) **CLAIM**

I claim the ornamental design for a Christmas tree tent, as shown and described.

DESCRIPTION

FIG. 1 is a perspective view of the Christmas tree tent;

FIG. 2 is a front view thereof with flaps open;

FIG. 3 is a left side view thereof;

FIG. 4 is a right side view thereof;

FIG. 5 is a back view thereof;

FIG. 6 is a front view thereof; and,

FIG. 7 is a front view thereof with flaps closed.

The broken lines shown represent environment only and form no part of the claimed design.
